ABSTRACT OF THE DISCLOSURE

The invention here provides a more efficient centrifugal pump for hydraulic dredges wherein a rotating impeller having radially extending blades carried by spaced shrouds and wherein the outer faces of the shrouds have radially extending grooves which function as expeller vanes to remove sand and other particulate matter from the spaces between the shrouds and the inner wall or liner of the pump case.

OBJECTS OF THE INVENTION

It is among the objects of the present invention to provide a centrifugal dredge pump having an impeller mounted for rotation within a pump case and wherein the pump case is characterized by having a suction side head and an engine side head and wherein the impeller shroud adjacent the inner wall of the heads is characterized by having recessed expeller vanes to remove particulate matter from the space between the shrouds and the heads.

It is a further object of this invention to provide a dredge pump according to the preceding object wherein a recessed expeller vane is formed with at least one wall thereof being substantially normal to the radial face of the shroud.

It is a further object of the invention to provide an impeller as described in the preceding objects wherein a wall of the recessed expeller vane slopes downwardly and inwardly toward said normal wall at the radial face of the shroud.

It is a further object of this invention to provide a dredge pump impeller as described in the preceding objects wherein the recessed expeller vane curves outwardly to the periphery of the impeller so as to discharge the material carried by the vane at the periphery of the shroud and into the pump case discharge area.

THE PROBLEM

Centrifugal dredge pumps are usually designed for pumping a particular type of mixture comprising water and solids. The useful work performed by the pump is determined by the ratio of solids to water. The optimum design of a pump impeller for a particular type of mixture moves the maximum amount of solids for a given pump size and a given power unit.

Accordingly the impeller blades should have the maximum width permitted by the spaces between the suction side head of the pump and the engine side head of the pump. It will be understood that the shrouds ordinarily perform no pumping function and, therefore, should have a minimum wall thickness consistent with their load-carrying function and should have a minimum space between the outer wall of the shroud and the inner wall of the adjacent pump head. Excessive clearance in this area results in recirculation of water which is heavily loaded with solids. The abrasive effect of the solids increases the wear on both the shrouds and heads and the "load up" of the space between the shroud and the head with sand causes power losses and lowers the overall efficiency of the pump. Numerous attempts have been made to clean the space between the shrouds and the head of solids which

2

adversely affect the efficiency of the pump. One of such attempts has included the provision of raised expeller vanes in the form of ribs which project from the face of the shroud. Such expedients leave considerable space for the accumulation of spoil between such projecting ribs on the radial face of the shroud. Such prior art efforts are characterized by cavitation and recirculation of water and solids in the space between the projecting ribs.

THE SOLUTION OF THE PROBLEM

The present invention provides a pump impeller having a shroud wherein the outer radial wall of the shroud is provided with an expeller vane in the form of a groove or channel extending from the central area of the shroud to its periphery. Such grooves or channels function somewhat in the manner of centrifugal pumps so that the water and solids collected in the grooves will discharge radially.

Assuming that the same thickness of shroud for its load-carrying ability is utilized, a wider impeller blade may be used without widening the pump case. Accordingly with the present invention a narrower pump case may be employed as compared to the prior art devices having wiper vanes in the form of projecting ribs. Cavitation is minimized since the space between the recessed expeller vanes is occupied by the material of the shroud.

Other objects and advantages will appear from the following description and the appended drawings wherein:

FIG. 1 is a transverse sectional view of a dredge pump made according to the present invention;

FIG. 2 is a perspective view of the pump impeller made according to the present invention;

FIG. 3 is an elevation of the suction side of the pump impeller corresponding to a view taken at plane 3—3 of FIG. 2;

FIG. 4 is an elevation of the engine side of the pump impeller taken as indicated by plane 4—4 of FIG. 2;

FIG. 5 is a sectional view of the pump impeller taken as indicated by the plane 5—5 of FIG. 3; and

FIG. 6 is an elevation of the pump case showing the tangential discharge.

Referring to the drawings, the pump case is indicated in FIG. 1 in its entirety at 5. The pump case comprises an annular ring section 6 which carries the tangential pump outlet 6a. The suction side head 7 is secured to the ring 6 and the engine side head 8 is also secured to the ring 6. The pump impeller indicated in its entirety at 10 is mounted for rotation by engine shaft 9 which extends into the pump through a stuffing box 11 on the engine side head 8. The pump impeller 10 may be secured to the shaft 9 by a threaded connection 9a as shown or by other conventional drive means. The ring section 6 of the pump is provided with a tangential outlet 6a and said outlet 6a is connected to a discharge pipe.

The suction side head 7 is connected to a suction line 14 which in turn leads to a submerged cutter, and line 14 brings the material being dredged from the cutter to the pump. The suction side head 7 is provided with a suction side opening 15 which leads to the central area of the impeller 10. Preferably the suction side head 7 and the engine side head 8 are provided with annular head liners 7a and 8a, respectively. The head liners 7a and 8a are usually formed of wear-resistant alloys.

The impeller 10 comprises an integrally formed front shrouds 18, a back shroud 19, a hub 20, and impeller blades 21. In the embodiment of the invention here illustrated four curved blades are shown, but it will be understood that the number of blades employed will be varied from time to time depending on the characteristics of the solids and water which are to be pumped. The front shroud 18 is formed with recessed expeller vanes 22 and the back shroud 19 is provided with recessed expeller vanes 23. In the embodiment of the invention here illus-

trated the recessed expeller vanes correspond to the number of pumping blades 21, but this is not critical. For example, a four-blade impeller may be provided with two recessed expeller vanes. The important consideration from the design standpoint is that the blades and also the wiper vanes provide a balanced condition without eccentric mass. The front shroud 18 is provided with a suction opening 16 which is aligned with the suction head opening 15. Preferably the pump blades 21 curve outwardly from the central area of the impeller and the recessed expeller vanes 22 and 23 also curve outwardly in the shrouds. It will be noted that the vanes in the form illustrated curve along the path of the pumping blades. In this manner the cross-section or thickness of the shroud is maintained for its load bearing requirements. The load-carrying ability of the shroud is not reduced in an area which forms the expeller vane.

Preferably the recessed expeller vanes 22 and 23 each have one wall 22a and 23a which is substantially normal to the face of the shroud. This normal wall is related to the directional rotation of the impeller as indicated by the arrow 25. (See FIGS. 2 and 5.) The other side wall of each expeller vane is indicated as at 22b and 23b. The walls 22b and 23b preferably slope downwardly and inwardly to intersect the normal wall.

Although one form of the invention is described herein in considerable detail, it will be understood that numerous variations may be made therein without departing from the scope of the invention as defined in the following claims.

What is claimed is:

1. A centrifugal pump for a dredge comprising a pump case having an annular ring section, a suction side head having a flat smooth surface secured to said ring section, an engine side head having a flat smooth surface secured to said ring section, a drive shaft mounted for rotation in said engine side head, an impeller secured to said shaft within the pump case, a pump inlet in said suction side head, said impeller having a front shroud adjacent the flat smooth inner wall of said suction side head, said impeller having a back shroud adjacent the flat smooth inner wall of said engine side head, impeller blades carried between said shrouds, said front shroud having a central opening aligned with a central opening in said suction side head, said front shroud having recessed expeller vanes in the form of radially extending grooves in the wall of the shroud adjacent the inner wall of the suction side head, said recessed expeller vanes being in the form of V-shaped grooves which have one wall thereof normal to the radial face of the shroud and the other wall thereof at an angle to the face sloping in the direction of the pump rotation to facilitate filling the expeller vanes with sand and water.

2. A centrifugal pump as described in claim 1 wherein both the front and back shrouds are provided with recessed expeller vanes in the wall of the shroud adjacent the flat smooth surface of the front and back pump heads.

3. A centrifugal pump as described in claim 1 wherein the impeller blades between the shrouds curve outwardly from a central pump inlet area to the periphery of the

shrouds and the front edge of each impeller blade has a radial extent less than the radial extent of the front shroud and the rear edge of each impeller blade has a greater radial extent than the radial extent of the front shroud.

5 4. A centrifugal pump as described in claim 1 where the recessed expeller vanes curve outwardly from a central pump inlet area to the periphery of the shrouds to discharge sand and water carried by the recessed expeller vanes at the periphery of the shrouds.

10 5. A centrifugal pump as described in claim 1, wherein the recessed expeller vanes are curved outwardly at the same curvature and in the same shroud area as the main pump impeller blades carried between the shrouds.

15 6. A centrifugal pump for a dredge comprising a pump cas having an annular ring section, a suction side head having a flat smooth surface secured to said ring section, an engine side head having a flat smooth surface secured to said ring section, a drive shaft mounted for rotation in said engine side head, an impeller secured to said shaft within the pump case, a pump inlet in said suction side head, said impeller having a front shroud adjacent the flat smooth inner wall of said suction side head, said impeller having a back shroud adjacent the flat smooth inner wall of said engine side head, impeller blades carried between said shrouds, said front shroud having a central opening aligned with a central opening in said suction side head, said front shroud having recessed expeller vanes in the form of radially extending grooves in the wall of the shroud adjacent the inner wall of the suction side head, said recessed expeller vanes being in the form of V-shaped grooves, one wall of each of said grooves being normal to the radial face of the shroud to form a radial pumping surface, and a second wall of each of said grooves sloping upwardly toward the said radial face of the shroud and in a direction away from the direction of the pump rotation.
